ELECTRICAL MUSICAL INSTRUMENT

John M. Hanert, Park Ridge, Ill., assignor to
Hammond Instrument Company, Chicago, Ill.,
a corporation of Delaware

Application May 5, 1945, Serial No. 592,098

16 Claims. (Cl. 84—1.19)

1

My invention relates generally to electrical musical instruments and more particularly to improvements in the tone generating and controlling apparatus of melody type instruments.

In some types of melody instruments, that is, instruments which produce but one tone at a time, there has been employed a master oscillator supplying signals to a series of cascaded frequency dividers, such as shown, for example, in my copending application, Serial No. 519,838, filed January 27, 1944, and since abandoned. The master oscillator has customarily been of the inductance-capacitance tuned type. In this method of tuning an oscillator it becomes a matter of considerable expense to provide the necessary large number of capacitors which must be carefully selected and some of which must be very large.

It is therefore one of the primary objects of my invention to provide a melody instrument tone generating system having a master oscillator which is tuned by changing the amount of resistance in its tuning circuit.

A further object is to provide an improved apparatus for changing the frequency of a Wien bridge oscillator to a preselected frequency by successively changing the effective impedances in the circuits of the oscillator.

A further object is to provide a master oscillator tuning system which is tuned by the depression of playing keys, and in which the tuning circuits are arranged such that when the playing keys are depressed in a legato manner the oscillator will generate a frequency intermediate the frequencies to which it is tuned by the two keys, as an incident to changing to the frequency of the last depressed key.

A further object is to provide frequency generating apparatus for a musical instrument of the melody type in which relatively smooth glissando effects may be obtained.

A further object is to provide a secondary tuning circuit for smoothly and dependably obtaining a quarter-tone scale with but twelve keys to the octave.

Another object is to provide a keyboard musical instrument of the melody type in which simultaneous depression of two adjacent keys produces a tone whose frequency is related to one of the keys but detuned by a factor of a quarter tone.

A further object is to provide a tuning mechanism for an oscillator requiring changes in two circuits thereof, which will change the impedances in these two circuits in a predetermined sequence such that the oscillator does not stop oscillation during the tuning process.

2

A further object is to provide an improved means for tuning an oscillator of the Wien bridge type in which the oscillator does not stop oscillating as its frequency is changed but instead shifts gradually from one frequency to another to which it is being tuned.

Other objects will appear from the following description, reference being had to the accompanying drawings in which:

Figs. 1a, 1b and 1c together constitute a wiring diagram;

Fig. 2 is a diagrammatic representation of the key operated switches showing their sequence of operation;

Fig. 3 is a longitudinal sectional view of the manually operated dynamic volume control switch mechanism; and

Fig. 4 is an end elevational view thereof with a portion of the casing broken away to reveal the operating parts.

General description

The invention may be described generally as a melody instrument having a master oscillator of a resistance tuned Wien bridge type such for example as is shown in the Hewlett Patent No. 2,268,872. The master oscillator output is coupled to a series of pulse sharpening pentodes to change the generally sinusoidal oscillator output wave into rectangular waves and thereafter through a rectifier triode to convert the rectangular waves into sharply peaked unidirectional pulses. These pulses are impressed upon the input circuits of the first of a series of alternate pulse responsive frequency divider stages. Signals representing different musical tone qualities are derived from different portions of the circuits of each of these divider stages and are selectively impressed upon the input of a preamplifier, the output of which is provided with a plurality of selectively operable tone control filters. The signals of the quality thus selected and predetermined are supplied to an output and power amplifying circuit and translated into sound.

The Wien bridge oscillator is tuned by successively changing the effective impedance of each of its frequency controlling circuits in a predetermined sequence. In addition the operation of the keys under certain circumstances may cause the oscillator to be tuned to the frequency intermediate the adjacent semitone frequencies so as to make it possible to play a quarter-tone chromatic scale. Furthermore, the operation of each of the keys is effective to render the output amplifier capable of transmitting the sig-

nal, the rate of attack and decay of the tone being automatically controlled.

The oscillator is provided with a vibrato mechanism whereby its frequency may be continuously varied through a given range, such as 3%, at a periodicity in the order of 7 C. P. S. In addition the oscillator tuning means is provided with an optionally operable switch for opening one branch of the tuning circuit when no key is depressed. Through the time delay action of a thermistor impedance element, the approach to the steady state frequency of the oscillator is delayed, to produce an interesting musical effect when playing in a non-legato manner.

Oscillator and tuning means

The oscillator comprises a pair of beam power pentodes 10 and 11, each supplied with plate current from a suitable power supply, indicated as a +300 v. terminal, through load resistors R14 and R15. The screen grids 16 and 17 of these pentodes are connected to the +300 v. terminals through voltage dropping resistors R18 and R19 and are by-passed to ground through capacitors C29 and C21 respectively. The grid bias for the pentode 10 is provided by a thermistor 22 connected between its cathode 26 and ground. The cathode 21 of the pentode 11 is connected to ground through a self-bias resistor R23. The output of the pentode 10 is coupled to the input of the pentode 11 through a blocking capacitor C28 connected between the plate 30 of pentode 10 and grid 33 of pentode 11. The plate 31 of pentode 11 is connected, through a relatively large blocking condenser C34 and a de-generative feedback resistor R36, to the cathode 26 of the pentode 10. The plate 31 is also connected to grid 39 through a regenerative circuit including the capacitor C34, a conductor 40, one or more of a plurality of tuning resistors R42, conductor 44, and phase shift capacitor C46 having a parallel tuning capacitor C47. The grid 39 is also connected to ground through a phase shift network comprising a capacitor C50, having a tuning capacitor C52 in parallel therewith, and one or more of a plurality of resistors R54, depending upon which of the playing keys is depressed. The over-all tuning capacitors C41 and C52 preferably have a common operating means. The circuit including the resistors R42, and C46, C47 may be considered as the series feedback circuit, while the circuit including resistors R54, and C50, C52 may be termed the shunt feedback circuit.

The keyboard for playing the instrument is diagrammatically illustrated as comprising three octaves of keys bearing their customary note designations C to B. Each key operates four switches 60, 61, 62 and 63. As illustrated in Fig. 2, these switches are operated in a predetermined sequence by an actuator 67 which, upon depression of the key, will first cause closing of switch 60 and then switch 61. The switch 62 may close substantially simultaneously with the switch 60 but the switch 63 should not close until a short time after switches 60, 61 and 62 have been closed.

The switch 60, as previously indicated, makes contact with a bus conductor 40, while the switches 61, 62 and 63 respectively make contact with grounded bus bars 64, 65 and 66.

Alternate ones of the movable arms of switches 62 are connected to conductors 68 and 69 respectively. The conductor 68 is connected to the grid 39 of pentode 10 through a quarter-tone

interval tuning capacitor C70 while the conductor 69 is connected to said grid through a second quarter-tone tuning capacitor C71 whose value may be the same as that of the capacitor C70.

A vibrato apparatus is adapted to be connected to the grid 39 of pentode 10 to slightly vary the frequency of oscillation thereof upon closure of a single-pole double-throw switch 72. A vibratory grounded reed 74 is adapted to be maintained in vibration by an electromagnet 76 having one end of its winding connected to a suitable energizing source such as a terminal +50 v. of the power supply system, while its other terminal is connected to a contact 78 which completes a circuit through the winding when the reed is in the upper portion of its oscillatory swing. During approximately one half of the period of oscillation of the reed 74 it engages a contact 80 which is connected through a tuning capacitor C82 and switch 72 to the grid 39. When the vibrato is not desired, the switch 72 is turned to the off position in which event a capacitor C84 is connected between the grid 39 and ground, the value of the capacitor C84 being approximately one half that of the capacitor C82, thus compensating for the change in median capacity produced when the switch 72 is in its full line position and the vibrato in operation. An anti-spark resistor R86 is connected between the contact 78 and ground.

The output of the Wien bridge oscillator, comprising the pentodes 10 and 11 and their associated circuits, is in the form of a sinusoidal wave which may vary somewhat in amplitude during the interval that its frequency is being changed. In order that such transient changes in amplitude shall not be present in the tone signal ultimately produced, the output of the oscillator is transmitted through a series of pentodes 90, 92 which are biased so as to be amplitude limiting and thus convert the sine wave output of the oscillator into equal amplitude substantially vertical front rectangular waves. Since such amplitude limiting tubes and circuits are known, it is believed that no further description of the pentodes 90 and 92 is necessary.

The output circuit of the pentode 92 is coupled to the input circuit of a triode 94 which is biased to operate as a rectifier.

Frequency dividers

The output of the rectifier 94 is impressed upon the grids 98, 99 of alternate pulse responsive frequency divider triodes 100 and 101. The triodes 100 and 101 and their associated circuit elements are disclosed in greater detail in my copending applications, Serial Nos. 569,567 and 569,568, filed December 23, 1944. Application No. 569,567 matured into Patent No. 2,514,490 on July 11, 1950. Application No. 569,568 has since become Patent No. 2,468,062, issued April 26, 1949. In general, it may be stated that these triodes 100 and 101 operate to supply a rectangular wave at an output terminal 102 which has a frequency exactly one half that of the input frequency supplied from the rectifier triode 94. The signal appearing at the output terminal 102 is impressed upon the input circuit of a pulse sharpening and rectifying triode 104 which supplies a signal suitable for the operation of the next alternate plus responsive frequency divider stage.

The signal appearing at the terminal 102 is also impressed upon the input circuit of a triode 106 which operates as a rectifier and pulse generator. The pulses appearing in the output of the

triode 106 are not as sharp and are of greater duration than the pulses produced by the triode 104. The second, third and fourth divider stages are generally similar to the first divider stage and operate successively to halve the frequency supplied by the preceding stage. Similar reference characters have therefore been applied to the corresponding parts.

The signals produced in these various stages are adapted to be selectively transmitted to bus bar 110 upon closure of one or more of a plurality of switches 112, 113 and 114 to control the transmission of tone signals of the qualities indicated by the legends adjacent the switches. It will be noted that the switches 112 controlling the transmission to the bus bar 110 of the tones of the woodwind family, namely, tones containing predominantly the odd harmonic series, are derived from the output of the triode 100 through a suitable mesh comprising resistors R116, R117 and capacitors C119 and C120. This mesh is effective to attenuate undesirable high harmonics as well as to attenuate the lower order harmonics and thereby to produce a tone signal of rich clarinet-like quality.

Upon closure of the switch 113 a signal from the output of the triode 106 is impressed upon collector bus 110 through a mesh comprising resistors R122, R123 and a capacitor C126. This mesh together with the plate load resistor R128 and a shunt capacitor C130 is effective to produce a generally sawtooth wave closely simulating in tone quality the tones of bowed string or- chestral instruments. The odd harmonic family present at the terminal 102 is effectively changed due to the provision of a capacitor C124 of size to be substantially current limiting with respect to grid resistor R125 at the frequency produced when the highest key B of the keyboard is depressed, and due the rectifying action of triode 106.

The closure of the switch 114 results in supplying the signal from the output of triode 104 through a mesh comprising resistors R132, R133 and capacitor C134. The triode 104, due to the relative values of its current limiting blocking capacitor C136 and grid resistor R138, and due to its rectifying action, eliminates the odd harmonics present in the signal appearing at the terminal 102, with the result that the signal appearing at the switch 114 is of exceedingly bright tone quality closely simulating the effects of brass instruments such as the trumpet.

Output circuits

The signals thus supplied to the collector bus 110 are impressed upon the input circuit of a preamplifier triode 140 through a blocking capacitor C142. The output of the preamplifier triode 140 may have its effective tone quality varied by means of a suitable tone controlling filter 144 rendered selectively operative by opening one or more switches 146. The signal as thus modified by one or more of these filters is coupled by a transformer T148 to the grids of a pair of push-pull triodes 150, 151. The cathodes 152 of these triodes are connected to ground and coupled to the center tap 153 of the secondary winding of transformer T148 through an attack and decay capacitor C154. Normally, the triodes 150 and 151 are biased beyond cutoff through a resistor R156 connected between the center tap 153 and a suitable source of biasing potential indicated as terminal -50 v. The center tap 153 is connected through an attack resistor R158

to a conductor 160 which it will be noted (Fig. 1a) is connected to all of the playing key-operated switches 63 and may be connected through any one of these switches to the grounded bus 66. When thus connected the resistors R156 and R158 act as a voltage divider to decrease the bias on the triodes 150 and 151 at a rate determined by the capacitor C154 so as to obtain a relatively fast but transientless attack when a key is depressed, as well as a relatively fast transientless decay when the depressed key is released. Triodes 150 and 151 may be of the 6J5 type having a relatively sharp cutoff. The signal applied to their grids is, in general, of amplitude just sufficient to avoid producing distortion. Under these conditions, the signal amplitude will scan over substantially the entire linear portion of the grid voltage-plate current characteristic, and will thus be effective to modulate the plate current to a very considerable extent and thereby minimize the transient due to the direct unmodulated plate current which will occur because of the unavoidable slight dissimilarities in the two portions of the push-pull transmission system. Under these conditions, the tubes 150 and 151 will cause a very considerable degree of distortion during the attack and decay portions of the tone signals, but inasmuch as these portions of the signals occupy a very small period of time the summation and difference distortion terms resulting from the non-linearity of the grid voltage-plate current characteristics are not perceptible to the ear, and the overall result is that of a transientless attack and decay. This has the advantage that the exact similarity of the two sides of the push-pull system are not of great importance. The similarity of the two sides of the push-pull system are made practically identical insofar as the plate loading is concerned by using an output transformer T162 in which the number of turns between the center tap (which is connected to the high voltage terminal indicated as +300 v.) and the extremities are kept equal. This equality is relatively easy to maintain, since the commercial tolerance on the number of turns on a transformer may be held to a part in several thousand.

The secondary winding of transformer T162 is coupled to the input circuits of remote cutoff pentodes 164, 165. A volume adjusting resistor R166 is connected between the control grids of pentodes 164 and 165. The center tap 167 of the secondary of transformer T162 is connected to a bus conductor 168 through a decoupling resistor R170 and is connected to ground through a time constant capacitor C172. The conductor 168 is connected to ground through a voltage dividing resistor R174. A source of negative biasing voltage, indicated as a terminal -50 v., is normally connected to the conductor 168 through a plurality of resistors R176 of logarithmically graded values such that successive opening of these switches will cause the output of pentodes 164, 165 to increase in equal db steps of approximately 2 db.

As shown in Figs. 3 and 4 this dynamic volume control includes the resistors R176, which are adapted to be successively disconnected and connected to the conductor 168 upon manual operation of a key 180. The key 180 is mounted on a pair of channels 181 which are secured to leaf springs 182 by brackets 183. Secured to one of the channels 181 is an actuator 183 of insulating material, which is adapted, as the key 180 is depressed, successively to move contactor switch

arms 190 from contact with the bus 168. As best shown in Fig. 3, the key 180 is so mounted that the player may conveniently rest the ends of his fingers upon the lower part 192 of the top of the casing 193, while the palm of the hand is rested upon the key 180 and the wrist or forearm rests upon the elevated portion 194 of the top of the casing. By utilizing this mechanical structure for successively opening and closing the switches for the resistors R176, the player has a very accurate and sensitive control of the dynamic output of the instrument. For purposes of comfort and to avoid fatigue the springs 184 should be relatively light so that a minimum amount of energy is required for the operation of the key. Inasmuch as the fingers and wrist or forearm of the player are adequately supported it will be clear that the movement of the key 180 will be controllable with a high degree of alacrity so that musically interesting intensity envelopes may be imparted to successive notes in the musical composition being rendered.

The output of the pentodes 164, 165 is resistance capacity coupled to power amplifying pentodes 196, 197 and the output of the latter coupled by a transformer T198 to a speaker 200.

It has been previously pointed out that the attack and decay portions of the tonal envelopes produced due to the changes in grid bias on triodes 150, 151 as a result of depression of one of the keys and connection of the conductor 160 (Fig. 1b) to ground produces very rapid attack and decay characteristics. These attack and decay rates correspond to the most rapid attack and decay which would ever be conceivably useful in the musical rendition. As explained before, this is carried out in a transientless manner devoid of any electrical clicks or "thumps." Whenever a slow attack or decay is desired, as for instance, to produce an attack of a slowly bowed string or the decay of a pianolike tone, the key 180 is operated simultaneously with the depression of the appropriate playing key C to B (Fig. 1a). To produce a slow decay the playing key will be held down and the dynamic volume control key 180 gradually released.

Operation of the oscillator

The Wien bridge oscillator shown in Fig. 1a is of well known type in its general circuit arrangement but, as modified for use in a musical instrument, there are a number of novel features associated therewith. In tuning an oscillator of this type successively to different frequencies, by varying a pair of resistors or a pair of capacitors in the conventional manner it is found that undesirable transients may be produced.

In using the means disclosed in this application for tuning the oscillator, novel and musically interesting effects are obtained because the transient produced by the oscillator when successive keys are played in a legato manner is of undiminished amplitude, that is, the oscillator never ceases oscillation. In addition the oscillator generates an intermediate frequency for each pair of legato notes that are played. For instance, when playing from a C key to an E key in a legato manner an intermediate frequency will be generated upon the depression of the E key, and the pitch of such intermediate tone will be approximately that of the intermediate D note. The sounding of this D note is very pleasing to the ear. In a musical sense it is perceived as a form of smooth glissando between C, D and E. To accomplish this result it is necessary that the os-

cillator shall not cease oscillating, and, in addition, shall successively generate two discreet frequencies as the second of a pair of playing keys is depressed in a legato manner.

By reference to Fig. 1a it will be seen that when a plurality of playing keys are simultaneously depressed, the resistors R42 associated with keys below the highest depressed key are not effective in the tuning circuit. Similarly, it will be noted that upon closure of two key switches 61, the switch of the lower key does not have any effect in the tuning circuit since such lower resistances are effectively connected to ground. Therefore, when two or more keys are simultaneously depressed the highest of such depressed keys will determine the steady state frequency of oscillation. However, when two keys are successively depressed in a legato manner (assuming the last depressed key is higher than the first depressed key) there will be a certain time interval during which both switches 60 respectively associated with these two keys are closed, while only the switch 61 associated with the lower of the depressed keys is closed. During this limited time interval, the oscillator bridge circuit will be unbalanced and the frequency at which it oscillates will be intermediate the frequencies of the notes of the two depressed keys. It is also apparent that the oscillator cannot possibly stop oscillating during this interval because the impedance between the plate 31 and the grid 39 has been reduced from that value which corresponds to the balanced bridge condition. Therefore, the oscillator departs in operation from the usual concept of the Wien bridge oscillator and becomes a form of multivibrator in which the new frequency is determined by a large number of parameters. However, in this condition of successive feedback energization, the frequency of oscillation will always lie approximately midway between those of the two depressed keys when the intervals are relatively small, as is usual in music. If an oscilloscope were connected to the plate 31 it would be observed that the oscillator never ceases oscillation when the above described tuning sequence is employed. Thus the transient contains very little low frequency, its energy being concentrated mainly at the frequencies corresponding to the first of said keys, the frequencies of the interval between the two depressed keys, and, as the steady state is reached, the frequency of the second depressed key. There is no opportunity for a low frequency thump which might occur, for instance, if the switches 60, 61 were operated in the reverse sequence. In the latter case an undesirable thump would occur because the feedback from the plate 31 to the grid 39 would be insufficient during the time that both switches 60 and only one of the switches 61 are closed. The oscillator will likewise be tuned to an intermediate frequency when notes are played in a legato manner down the scale as well as up the scale.

The switches 62 and the circuit elements associated therewith are provided to enable the player to obtain twice as many tones as playing keys, the arrangement being such that whenever two adjacent semitone keys are simultaneously depressed both capacitors C70 and C71 will be connected in the circuit between grid 39 and ground. Thus the reactance of the circuit including these capacitors is doubled when both keys are depressed. The values of C70 and C71 are such that this change in reactance in this circuit will be sufficient to decrease the frequency

of oscillation by one quarter of a full tone interval. Thus, for example, when the key C is depressed and held depressed while the key C# is depressed, the oscillator will generate a frequency which is the mean between the frequencies of the notes C and C# and, as soon as the key C is released, the oscillator will generate the frequency of the note C#. It will thus be seen that the number of discrete frequencies available to the player of the instrument is substantially twice the number of keys. Since a quarter-tone interval is a relatively slight pitch change, if the player will play the chromatic scale in the customary legato manner, the musical effect will be that of a smooth glissando. The quarter-tone steps are so small that when the glissando is taken at a musical rate, the ear is unable to resolve the effect into its discrete quarter-tone increments but rather perceives the overall effect as a perfectly smooth glissando transition from one note to the other. The glissando that is obtained is a great improvement over the ordinary glissando effect produced by keyboard instruments such as the piano and organ in which pitch accuracy of the ear is sufficient to resolve it into the chromatic steps.

When switch 202 is closed, the oscillator is normally operating at its lowest frequency but no sound is heard from the speaker because the control switches 63 are not closed. When switch 202 is open, it will be seen that there is no energy feedback connection between the plate 31 and the grid 39. Therefore, there is no energy feedback and no oscillations occur. When any playing key is depressed, the oscillator must start from zero frequency and arrive at the desired frequency of steady oscillation. The rate at which it arrives is controlled by the thermo-resistance properties of the thermistor 22. When this thermistor is in the form of a 6 watt 115 volt tungsten incandescent lamp, the time required for the oscillator to reach its steady state frequency may be approximately 50 milliseconds. When a playing key is depressed, the amplifying and output system will be effective to transmit the tone signal during at least a portion of this 50 millisecond interval. Ordinarily the listener will be aware of the rise in frequency during approximately 40 of this 50 millisecond time interval. The effect produced is comparable to that of some mechanical musical instruments, such as the trumpet and saxophone. For instance, if a key is depressed repeatedly with rapidity, the oscillator may never attain the final steady frequency corresponding to the actuated key, but will always be in the transient condition of changing its frequency, increasing in frequency while the switches 60, 61 are closed and decreasing in frequency while the switches 60, 61 are open.

Similarly, many novel and entertaining effects may be produced by playing a melody rapidly in the form of short staccato notes. Under these circumstances, the oscillator may be in the condition of changing its frequency most of the time and only attain its steady state when a note is accented by holding it depressed for 50 milliseconds. This effect is highly desirable as providing an entertaining variation in contrast to the normal organlike tones.

It will be understood that an oscillator of the Wien bridge type such as disclosed herein may be tuned by simultaneously changing the capacitance of the two regenerative feedback circuits or simultaneously changing the resistances in these two circuits. This will be evident from

a consideration of the formula for the frequency of oscillation of a well balanced and properly designed oscillator which is:

$$f = \frac{1}{2\pi\sqrt{R_1 R_2 C_1 C_2}}$$

in which R_1 and C_1 are the total resistance and capacitance of the series feedback circuit and R_2 and C_2 are the total resistance and capacitance of the shunt feedback circuit. Thus in Fig. 1a the resistors R42 and R54 could be replaced by capacitors if the capacitors C46, C47 and C50, C52 were replaced by resistors. Under these circumstances the capacitors C70 and C71 in the quarter tone scale would have resistors of suitable values substituted therefor, and the capacitors C82 and C84 of the vibrato mechanism would likewise be replaced by resistors. If these capacitors and resistors are thus interchanged, the relationship of the keyboard shown in Fig. 1a with respect to the circuits would have to be reversed, that is, the lowest key would operate the switches 60 to 63 at the right hand end of the diagram and the highest key would operate the switches 60 to 63 at the lowermost end of the diagram, etc. Under these conditions, the instrument would operate to select the frequency corresponding to the lower or lowest of two or more depressed keys. The sequence of operation of the switches 60 to 63 would be the same as heretofore described.

The oscillator shown in Fig. 1a is of well known construction and the values of the various components will therefore be known or readily available to those skilled in the art. However representative values may be given, assuming the pentodes 10 and 11 are of the 6V6 type.

C20	-----	microfarads	.3
C21	-----	do	.3
C22	-----	do	.3
C46	-----	do	.006
C47	-----	do	.0006
C50	-----	do	.006
C52	-----	do	.0006
C70	-----	do	.0008
C71	-----	do	.0008
R14	-----	ohms	5,000
R15	-----	do	10,000
R19	-----	do	10,000
R36	-----	do	3,500

The total resistance of the series of R42 resistors may be approximately 50,000 ohms, and similarly, the total resistance of the series R54 resistors may likewise be 50,000 ohms. The resistor R42 which is connected to the conductor R44 may have a resistance in the order of 6,250 ohms whereas the next adjacent resistor R42 may have a value 6% of that of the highest resistor R42, each resistor R42 having a value of about 6% of the total resistance of the preceding series of resistors R42. The values of R54 may be computed in a similar manner.

The operation of the various components and sections of the instrument have been included with the detailed description thereof. In general, the instrument is designed for use as an orchestral instrument. Normally, the player will manipulate the playing keys with his right hand and operate the dynamic volume control key 180 with his left hand. In most uses of the instrument the player will play legato-wise on the keyboard and appropriate phrasing for both legato and non-legato playing will be obtained by the

11

depression of the dynamic control key 180. For rapid staccato playing however, the player will reverse the operation and maintain his left hand control stationary while playing the right hand pitch determining keys in a detached non-legato manner.

The volume adjustment resistor R166 will usually be adjusted initially to suit the output of the instrument to the size and acoustic characteristics of the room in which the instrument is to be played.

Due to the possibility of selecting one or more of three different tone families by the selective operation of switches 112, 113 and 114 and the possibility of further modifying the tone qualities by operation of switches 146, the range in variation of tone qualities available is very great. These quality controls are disclosed in greater detail and are claimed in my copending application Serial No. 87,913, filed April 16, 1949, and the apparatus shown particularly in Figs. 2, 3, and 4 is disclosed and claimed in my copending application Serial No. 169,891, filed June 23, 1950.

While I have shown and described a particular embodiment of the invention, it will be apparent to those skilled in the art that numerous modifications and variations may be made in the form and construction thereof, without departing from the more fundamental principles of the invention. I therefore desire, by the following claims, to include within the scope of my invention all such similar and modified forms of the apparatus disclosed, by which substantially the results of the invention may be obtained by substantially the same or equivalent means.

I claim:

1. In an electrical musical instrument having a group of playing keys, the combination of a Wien bridge oscillator having a series feedback circuit and a shunt feedback circuit, each of said circuits including resistances determinative of the frequency of oscillation; means operated by the playing keys effectively to vary the values of the resistances in both of said circuits; a pair of capacitors, switches operable by alternate playing keys to connect one of said capacitors in the shunt circuit; and switches operated by the intermediate playing keys to connect the other of the capacitors in the shunt circuit, said capacitors having such values that when two adjacent keys are depressed at the same time both of said capacitors will be effective in the shunt circuit and will cause the oscillator to operate at a frequency intermediate the frequencies at which it would oscillate upon the separate depression of said adjacent keys.

2. In an electrical musical instrument having a group of playing keys, the combination of a frequency generator of the Wien bridge type having a series feedback circuit and a shunt feedback circuit respectively provided with adjustable resistances, the values of which determine the frequency of oscillation of the oscillator; a plurality of switches operated by each of the playing keys, said switches being effective successively upon ascending the musical scale to decrease the effective values of corresponding tuning resistances in each of said circuits; and means associated with said switches and keys effective upon depression of a key to cause a change in the resistance in the series circuit prior to a change in the resistance of the shunt circuit, and upon release of a key to change the resistance in the

12

shunt circuit prior to changing the resistance in the series circuit.

5 3. In an electrical musical instrument having a group of playing keys, the combination of a frequency generator of the Wien bridge type having a series feedback circuit and a shunt feedback circuit respectively provided with tuning impedances, the values of which determine the frequency of oscillation of the oscillator; a plurality of switches operated by each of the playing keys, said switches being effective successively upon ascending the musical scale to decrease the effective values of corresponding tuning impedances in each of said circuits; and means associated with said switches and keys effective upon depression of a key to cause a change in the impedance in the series circuit prior to a change in the impedance of the shunt circuit, and upon release of a key to change the impedance in the shunt circuit prior to changing the impedance in the series circuit.

10 4. In an electrical musical instrument having a group of playing keys, the combination of a Wien bridge oscillator having a series feedback circuit and a shunt feedback circuit, each of said circuits including resistive and capacitative impedances determinative of the frequency of oscillation, means operated by the playing keys effectively to vary the values of the impedances of one character in both of said circuits; a pair of impedances of the other character, switches operable by alternate playing keys to connect one of said last-named impedances in the shunt circuits; and switches operated by the intermediate keys to connect the other of said last-named impedances in the shunt circuit, said last-named impedances having such values that when two adjacent keys are depressed at the same time both of said impedances will be effective in the shunt circuit and will cause the oscillator to operate at a frequency intermediate the frequencies at which it would oscillate upon the separate depression of said adjacent keys.

15 5. In an electrical musical instrument having a group of playing keys, the combination of a Wien bridge oscillator having a series feedback circuit and a shunt feedback circuit, each of said circuits including resistances determinative of the frequency of oscillation; means operated by the playing keys effectively to vary the values of the resistances in both of said circuits; a pair of capacitors of equal value; switches operable by alternate playing keys to connect one of said capacitors in the shunt circuit; and switches operated by the intermediate playing keys to connect the other of the capacitors in the shunt circuit; said capacitors having such values that when two adjacent keys are depressed at the same time both of said capacitors will be effective in the shunt circuit and will cause the oscillator to operate at a frequency intermediate the frequencies at which it would oscillate upon the separate depression of said adjacent keys, where- 20

25 6. In an electrical musical instrument having a group of playing keys, the combination of a frequency generator of the Wien bridge type having a series feedback circuit and a shunt feedback circuit respectively provided with adjustable tuning resistances, the values of which determine the frequency of oscillation of the oscillator; a plurality of switches operated by each

of said keys; said switches being effective successively upon ascending the musical scale to decrease the effective values of corresponding tuning resistances in each of said circuits; means associated with said switches and keys effective upon depression of a key to cause a change in the resistance in the series circuit prior to a change in the resistance of the shunt circuit, and upon release of a key to change the resistance in the shunt circuit prior to changing the impedance in the series circuit; a vibrato capacitor; and cyclically operating means alternately to connect and disconnect the vibrato capacitor in the shunt feedback circuit at a rate in the order of 7 cycles per second, thereby to raise and lower the frequency of the oscillator in a manner to produce a vibrato effect.

7. In an electrical musical instrument having a group of playing keys, the combination of a frequency generator of the Wien bridge type having a series feedback circuit and a shunt feedback circuit respectively provided with adjustable tuning resistances, the values of which determine the frequency of oscillation of the oscillator; a plurality of switches operated by each of the playing keys, said switches being effective successively upon ascending the musical scale to decrease the effective values of the tuning resistances in each of said circuits; means associated with said switches and keys effective upon depression of a key to cause a change in the resistance in the series circuit prior to a change in the resistance of the shunt circuit, and upon release of a key to change the resistance in the shunt circuit prior to changing the resistance in the series circuit; and a switch operable, when all the key operated switches are open, upon closure to connect the maximum tuning resistance in the series feedback circuit and upon opening to open the series feed-back circuit.

8. In an electrical musical instrument having a group of playing keys, the combination of a frequency generator of the Wien bridge type having a series feedback circuit and a shunt feedback circuit respectively provided with adjustable tuning impedances, the values of which determine the frequency of oscillation of the oscillator; a plurality of switches controlled by each of the playing keys, said switches being effective successively upon ascending the musical scale to change the effective values of corresponding tuning impedances in each of said circuits; and means associated with said switches and keys effective upon depression of a key to cause a change in the impedance in the series circuit and thereafter a change in the impedance of the shunt circuit, and upon release of a key to cause a change in the impedance in the shunt circuit and thereafter a change in the impedance in the series circuit.

9. Tuning means for a Wien bridge oscillator having a pair of electron discharge devices provided with two frequency determining circuits, each of said circuits including resistance and capacitance impedance elements, and key operated means operative to change the effective values of corresponding impedances in both of said circuits in a predetermined sequence, one after the other.

10. In an electrical musical instrument having a tone signal generating system including a bridge type oscillator having shunt and series regenerative feedback circuits the impedances of which determine its frequency of oscillation, the

combination of a plurality of playing keys; a pair of switches operated sequentially by each of said keys, and means controlled by said switches to change corresponding tuning impedances of each of the circuits; the first operated switch being in the series feedback circuit.

11. Tuning means for a Wien bridge oscillator having a pair of electron discharge devices provided with two frequency determining circuits, each of said circuits including resistance and capacitance impedance elements, and key operated means operative to change the effective values of the resistance impedance elements in both of said circuits in a predetermined sequence, one after the other.

12. In an electrical musical instrument having an oscillator and a plurality of playing keys, an oscillator tuning circuit having means for changing its impedance in accordance with the operation of the keys to generate the frequencies of the semitone musical scale, and additional tuning means rendered effective upon the concurrent depression of two adjacent keys to change the frequency of oscillation of the oscillator to a frequency intermediate the frequencies to which the oscillator would be tuned by the separate depression of the two adjacent keys.

13. In an electrical musical instrument having an oscillator and a plurality of playing keys, an oscillator tuning circuit having means for changing its impedance in accordance with the operation of the keys to generate the frequencies of the semitone musical scale, and additional tuning means to change the frequency of oscillation of the oscillator to frequencies intermediate the semitone frequencies of the musical scale upon concurrent depression of the keys for adjacent semi-tones.

14. In an electrical musical instrument having a plurality of playing keys, an oscillator for determining the frequency of the electrical tone signals produced, said oscillator having a tuning circuit including impedances of different character, means operated by the playing keys progressively to change the effective values of impedances of one character so as to tune the oscillator to the frequencies of the semitone intervals of the tempered musical scale upon successive depression of the keys, and additional tuning impedances of different character rendered effective by the keys to change the frequency of oscillation of the oscillator by a quarter-tone interval when two adjacent keys are depressed concurrently.

15. In an electrical musical instrument having a plurality of playing keys, and an oscillator for determining the frequency of the electrical tone signals produced, said oscillator having a tuning circuit including resistive and capacitative impedances, means operated by the playing keys progressively to change the effective values of impedances of one character so as to tune the oscillator to the frequencies of the semitone intervals of the tempered musical scale upon successive depression of the keys, and additional tuning impedances of the other character rendered effective by the keys to change the frequency of oscillation of the oscillator by a quarter-tone interval when two adjacent keys are depressed concurrently.

16. In an electrical musical instrument having a plurality of playing keys, an oscillator for determining the frequency of the electrical tone signals produced, said oscillator having a tuning

15

circuit including impedances, means operated by the playing keys progressively to change the effective values of the impedances so as to tune the oscillator to the frequencies of the semi-tone intervals of the tempered musical scale upon successive depression of the keys, and additional tuning impedances rendered effective by the keys to change the frequency of oscillation of the oscillator by a quarter tone interval when two adjacent keys are depressed concurrently.
